CIRCUIT BREAKER

Otto Jensen, Malvern, Pa., assignor to I. T. E. Circuit Breaker Company, Philadelphia, Pa., a corporation of Pennsylvania

Application September 30, 1944, Serial No. 556,502

8 Claims. (Cl. 200—148)

11

My present invention relates to circuit breakers and more particularly to high speed air blast circuit breakers intended to carry relatively heavy currents at high voltage.

My invention contemplates the formation of an air blast circuit breaker in the form of a simple vertical structure embracing the contact mechanisms and the arc chute mounted by means of an insulator on an air storage tank.

My invention also contemplates the arrangement of contacts of the circuit breaker so that they will be aligned in the principal direction of air blast flow, preferably vertically aligned; but the circuit breaker structure will be so arranged that the air blast at the moment it strikes the arc caused by the separation of the contacts will be substantially transverse to the said arc.

My invention thus contemplates retaining all of the advantages of vertical movement of the air blast substantially along the path of separation of the contacts combining therewith, however, a somewhat sinusoidal internal arrangement which will enable the blast to strike the arc transversely at the area in which the arc is generated.

Accordingly, a primary object of my invention is the formation of an air blast circuit breaker having a novel arc chute. A corollary object of my invention is the formation of an air blast arc chute so arranged that although the air will move substantially along the path of movement of the contacts, the air blast will strike the arc transversely at its area of generation.

Another object of my invention is a novel formation of arc extinguishing horns and a novel arrangement for providing a by-pass current for the arc extinguishing system.

Another object of my invention is the arrangement of the circuit breaker so that the initial opening movement of the movable contact breaks the current flow while further movement isolates the arc horn connected to the movable contact terminal through the movable contact and thus provides an isolation switch.

Another object is the formation of the air blast path so that in the event an arc should maintain itself even in the isolation position of the contact, it will be subject to a transverse blast.

These and many other objects of my invention will become apparent in the following specification and drawings in which

Figure 1 is a side view in cross-section of my novel circuit breaker;

Figure 2 is a cross-sectional view taken on line 2-2 of Figure 1 looking in the direction of the arrows.

Referring now to Figures 1 and 2, the contact arrangement consisting of the main stationary contact structure 10, the main movable contact structure 11, and the intermediate contact

structure 12, have already been specifically described in the co-pending application of Arthur S. Caswell, Serial No. 529,439, filed April 4, 1944, entitled "Circuit breaker contacts," and assigned to the assignee of the present application.

The arc extinguisher 13 has been more specifically described in the co-pending application of Otto Jensen, Serial No. 406,813, filed August 14, 1941 (now Patent No. 2,353,729, and assigned to the assignee of the present invention.

The circuit breaker itself comprises a principal housing 20 which is secured by bolts 21 and a clamping ring 22 to the lower connecting member 23, which has a terminal 24. The entire circuit breaker structure in the housing 20 is mounted on the lower hollow insulator 25 which has the internal air passage 26.

20 Insulator 25 is preferably mounted on top of a compressed air tank and suitable controls may be provided therefor, as for instance described in the co-pending application of Otto Jensen et al., Serial No. 410,260, filed September 10, 1941.

The upper end of the insulator 25 has a reinforcing collar 28 secured thereto in any suitable manner and a gasket or washer 29 is placed between the collar 28 and the connecting member 23, and the connecting member 23 is bolted to the collar 28 by the bolts 30 which may be provided with suitable insulating bushings.

30 The main movable contact 11 comprises a vertical sliding rod having an arcing contact surface 32 and main contact surfaces 33, 33. The main stationary contact 10 is provided with main stationary contact members 34, 34 and an arcing
35 contact member 35. The main stationary contact members 34 and the arcing contact 35 are secured in a housing 37 at the end of the curved conductive bar 38. The curved conductive bar 38 is provided with lateral flanges 39 and 40, which are secured by means of bolts 41, 41 to the side internal frame supporting collars 42, 42.

These frame supporting collars 42 are secured to the sides of the housing 20 by means of bolts 43, 43. The conductive bar 38 is curved at 38a 45 to form an arc horn. The upper terminal 45 of the circuit breaker is secured by means of the bolt 46 to the end of the conductive bar 38. The upper end of the arc horn 38a has an upwardly extending connecting tongue 47 which is conductively engaged by the clip 48 of the arc chute 50 13.

The intermediate contact members 12 comprise a pair of opposite contacting elements 50, 50 which may contact with the sides of the movable contact member while it is between them. The members forming the intermediate contact 12 are contained in the housing 52 which is secured by bolts 53, 53 to the centrally located internal collar 55 within the housing.

60 The internal supporting collar 55 is supported

from the upper collar 42 by means of the post 60 which is secured by the bolt 61 to the upper supporting collar 42 and by the bolt 62 to the lower supporting collar 55. It is also supported from the upper supporting collar by the insulating tube 65 which is, at 66, threaded into an appropriate opening 67 of the lower supporting collar 55, and which tube is at the upper end closed by the plug 69 and secured to the upper supporting collar 55 by the bolt 68.

The intermediate or lower supporting collar 55 is a substantially solid member except for the opening 70 through which the movable contact member passes, and the opening 67 which provides a passage for the blast air. The upper supporting collar 42 is substantially solid and closed at the center and at its left-hand side, but is substantially open and consists substantially of a pair of spaced tines at its right-hand side to provide a free passage for air. Also the collar 42 does not extend entirely over to the right-hand wall (Figure 1) of the housing 20, so that a free passage for the arc horn 138a is provided.

As will be seen, current enters through the upper terminal 45, passes along the arcing horn 38a to the upper contact structure 10; then passes through the movable contact 11 when the same is in engagement with the upper contact structure; then through the lower connecting member 23 to the lower terminal 24.

As described in co-pending application of Arthur S. Caswell, above mentioned, the main stationary contact members 37 are pressed toward the movable contact by means of the springs 75. They are also pressed downwardly by the spring 76 in order to engage the bottom wall 71 of the housing which is in close conductive relation with the connecting bar 38.

The arcing contact member 35 is spring compressed by means of the spring 80 toward the movable contact. When the movable contact has engaged the stationary contact, the arcing contact surface 32 forces the stationary arcing contact 35 back, so that the main contact surfaces 33 of the movable contact may engage the main contact surfaces 34 of the stationary contact.

The intermediate contact elements 50 are pressed toward the movable contact by means of the spring 82 in the same manner as are the stationary contact members, and are pressed into conductive engagement with their housing by means of the springs 83. Thus, the movable contact may slide with respect to the intermediate contact elements 50 of the intermediate contact 12, and carry current thereto.

The lower connecting member 23 also carries a contact housing 90 secured thereto in any suitable manner, as for instance by the bolts 91. The contact members 92, 92 in the lower contact housing 90 are biased into engagement with the movable contact 11 by the springs 93 and are biased into engagement with their housing by the spring 94. The lower contact members 92 thus carry current from the movable contact 11 to the lower connecting member 23 and thence to the lower terminal 24.

In each case these various contact members avoid the necessity for flexible leads or pigtails. The intermediate contact section 12 comprising the contact members 50, furnish the current for the arcing horn 138a. That is, the arcing horn 138a is connected at its lower end to the upper portion of the housing for the intermediate contact structure 12.

The air passage thus formed consists of the

following: the tube 26 in the insulating member 25, which tube extends substantially alongside the path of movement of the lower movable contact 11; the lower air chamber 100 is connected by the tube 65 to the area where the arc is drawn; the tube 65 is provided with an opening 102 opposite the arcing area. The air thus flows up the passage 26 into the chamber 100 and then through the relatively narrow tube 65, where the relatively confined exit opening provides for a high speed air blast. The air flows through the opening 102 into the section 104 where the arc is drawn, and then flows up through the passage 105 into the upper chamber 106, and then into the arc extinguisher 13.

When the movable contact separates from the stationary contact, the contact surfaces 33 and 34 separate first, while the spring 80 drives the stationary arcing contact 35 toward the movable arcing contact 32 to maintain engagement therebetween. The stationary arcing contact 35 is brought to a stop by the flanges 109 only after the main contact surfaces have separated. Consequently, the arc is drawn between the stationary arcing contact surfaces 35 and the movable arcing contact surface 32.

The air blast is initiated at the time that the contacts begin to separate so that by the time the arc is drawn between the arcing contact surfaces in the area 104, the full force of the air blast strikes the arc. The arc is blown on to the arcing horns 38a and 138a and up into the upper chamber 106, and then up into the arc chute 13 where it is extinguished.

A current supply is maintained to the left-hand arcing horn 38a by reason of its connection to the terminal 45. A current supply for the right-hand arcing horn 138a of Figure 1 is provided from the movable contact 11 through the intermediate contact structure 12, to which the right-hand arcing horn 138a is connected. The upper end of the arcing horn 138a is provided with a tongue extension 115, similar to the tongue extension 47 previously described, which tongue extension is engaged by the connecting clip 116 corresponding to the connecting clip 48, previously described.

Arc horn 138a is isolated from its terminal 24 when the moving contact 11 leaves the intermediate contact 12. Any arc which may nevertheless hang on between the arcing contact surfaces 32 and 35 after the movable contact leaves the intermediate contact will be extinguished by the cross-blast in chamber 108.

The arc extinguisher 13 has already been described in the application of Jensen, Serial No. 406,813, now Patent No. 2,353,729, and requires no further description here. Essentially, however, the arc is blown up into the arc chute with the roots of the arc at the terminal plates 120 and 121, and into the arc extinguishing high resistance metallic plates 122. Each pair of plates 122 is connected together to form a high resistance U-shaped plate, so that as the arc is blown up between the adjacent U-shaped plate, the increasing resistance of the plates is inserted in series with the arc in addition to the cooling effect of the plates.

The vented cover 130 for the entire structure 70 also is described in the said application Serial No. 406,813, now Patent No. 2,353,729, and is secured to the top of the housing 20 by means of bolts 131 passing through matching flanges 132, 133. The removal of the bolts 131 enables 75 removal of the cover 130 and the withdrawal of

the arc chute 13 which is connected to the upper ends of the arcing horns only by the clips 48 and 116. After inspection of the arc chute, it may be re-inserted through the top of the housing 20 so that the clips 116 and 48 engage respectively the tongues 115 and 47.

By the means herein described, a sinuous air blast arc chute is arranged in such a manner that the air essentially travels longitudinally along the path of movement of the arc; but at the portion of the air path where the air is directed against the arc, the path of movement of the air is transverse to the arc. This arrangement therefore makes possible the simplified mounting of the entire circuit breaker structure right on top of the air storage tank for the simplified short connection to the air storage tank which avoids the possibility of loss of pressure and reduces the occurrence of leaks.

Also this arrangement makes possible the combination of a horizontal blast of air which is transverse to the movement of vertically movable contacts with an overall vertical movement of the air. That is, the air blast up to the time it reaches the arc moves vertically and after it engages the arc and blows the same into the arc chute, it again moves vertically.

The vertical upward movement of the air after the arc has been engaged avoids a substantial amount of back pressure and in fact utilizes the 30 tendency of the heated or ionized air to rise to relieve the pressure.

In the foregoing I have described my invention only in connection with a simplified, readily understood embodiment thereof. Many variations and modifications of my invention should now be clear to those skilled in the art. Accordingly, I prefer to be bound not by the specific disclosure herein but only by the appended claims.

I claim:

1. In a circuit interrupter having a movable contact and a complementary contact, a fluid blast arc extinguisher comprising a principal chamber; and a source of fluid under pressure connected to said principal chamber; said principal chamber being arranged to direct said fluid in a path substantially parallel to the path of movement of the movable contact; means controlled by said movable contact in the first part of its movement for interrupting the circuit controlled by said interrupter and in the further movement effecting an isolating break in series with said interruption; and means in said chamber for directing said fluid in a sinuous path; said path intercepting the path of movement of the movable contact in a plurality of regions.

2. In a circuit interrupter having a movable contact and a complementary contact, a fluid blast arc extinguisher comprising a principal chamber; and a source of fluid under pressure connected to said principal chamber; said principal chamber being arranged to direct said fluid in a path substantially parallel to the path of movement of the movable contact; and a partition in said principal chamber extending across the path of movement of said movable contact; an opening in said partition; the end of said movable contact extending through said opening in said partition on one side of the partition when the contacts are engaged, said movable contact being withdrawn from said opening and on the other side of said partition when said contacts are fully disengaged; the connection between said source of fluid and said principal

chamber being at one side of the axis of said principal chamber; an additional opening in said partition on the other side of the axis of said principal chamber, the fluid being guided by said partition and said additional opening in a path transverse to the arc to extinguish any arc which may extend from said complementary contact through said first mentioned opening in the partition to the movable contact; means above said partition associated with said additional opening for guiding said fluid transversely of the path of movement of the movable contact in the region of initial separation of the contacts, said complementary contact having an arcing horn associated therewith; said partition carrying an intermediate contact at its first mentioned opening; said movable contact engaging said intermediate contact only while said movable contact extends through said opening in said partition; another arcing horn connected to said intermediate contact.

3. In a circuit interrupter; a housing defining a principal chamber; a movable contact supported adjacent one end of said chamber; a complementary contact supported in said chamber remote from said movable contact; said movable contact being movable from the end of the chamber near which it is supported into engagement with said complementary contact; a partition in said chamber between said movable contact support and said complementary contact; an opening in said partition; said movable contact extending through said opening when said contacts are engaged, and being remote from said partition when said contacts are fully disengaged, said complementary contact having an arcing horn associated therewith; said partition carrying an intermediate contact at said opening; said movable contact engaging said intermediate contact only while said movable contact extends through said opening in said partition; another arcing horn connected to said intermediate contact.

4. In a circuit interrupter; a housing defining a principal chamber; a movable contact supported adjacent one end of said chamber; a complementary contact supported in said chamber remote from said movable contact; said movable contact being movable from the end of the chamber near which it is supported into engagement with said complementary contact; a partition in said chamber between said movable contact support and said complementary contact; an opening in said partition; said movable contact extending through said opening when said contacts are engaged, and being remote from said partition when said contacts are fully disengaged, said complementary contact having an arcing horn associated therewith; said partition carrying an intermediate contact at said opening; said movable contact engaging said intermediate contact only while said movable contact extends through said opening in said partition; another arcing horn connected to said intermediate contact, said other arcing horn being electrically isolated when said contacts are fully disengaged; said partition providing a substantial barrier between said contacts when said contacts are fully disengaged.

5. In a circuit interrupter; a housing defining a principal chamber; a movable contact supported adjacent one end of said chamber; a complementary contact supported in said chamber remote from said movable contact; said movable contact being movable from the end of the cham-

ber near which it is supported into engagement with said complementary contact; a partition in said chamber between said movable contact support and said complementary contact; an opening in said partition; said movable contact extending through said opening when said contacts are engaged, and being remote from said partition when said contacts are fully disengaged, said complementary contact having an arcing horn associated therewith; said partition carrying an intermediate contact at said opening; said movable contact engaging said intermediate contact only while said movable contact extends through said opening in said partition; another arcing horn connected to said intermediate contact, and an arc chute connected to said arc horns.

6. In a circuit interrupter having a movable contact and a complementary contact, a fluid blast arc extinguisher comprising an elongated principal chamber; and a source of fluid under pressure connected to said principal chamber, a stationary contact being mounted at one end of said chamber and said source of fluid under pressure at the other end of said principal chamber, said movable contact traversing said chamber axially, an intermediate contact dividing said chamber into an interrupting section and an isolating section; and means in said chamber for guiding said fluid under pressure to traverse first said isolating section and then said interrupting section.

7. In a circuit interrupter having a movable contact and a complementary contact, a fluid blast arc extinguisher comprising an elongated insulated principal chamber; and a source of fluid under pressure connected to said principal chamber; a stationary contact being mounted at one end of said principal chamber and said source of fluid under pressure being connected to the other end of said chamber, an arcing horn, an intermediate contact connected to said arcing

horn, said movable contact engaging both said intermediate and complementary contacts in closed position and on opening disengaging said stationary contact first and thereafter said intermediate contact to form an interrupting gap and an isolating gap; and means in said chamber for guiding said fluid traversing first the isolating gap and then said intermediate gap during movement of the movable contact in the region between the movable and complementary contacts.

8. In a circuit interrupter having a movable contact and a complementary contact, a fluid blast arc extinguisher comprising an elongated insulating principal chamber; and a source of fluid under pressure connected at one end of said principal chamber and a vent for contaminated gas at the other end of said principal chamber, means including said movable contact for establishing an interrupting break to be followed by an isolating break in series within said chamber in response to the continuous movement of said movable contact; means in said chamber for directing said fluid in a sinuous path to traverse the isolating break and then the interrupting break in the path of movement of said movable contact.
